UNITED STATES PATENT OFFICE.

DEL ROY F. FOWLER, OF MELROSE, PENNSYLVANIA.

PACKAGE FOR COTTON-BATTING.

No. 884,574.

Specification of Letters Patent.

Patented April 14, 1908.

Application filed July 20, 1905. Serial No. 270,472.

To all whom it may concern:

Be it known that I, DEL ROY F. FOWLER, a citizen of the United States, residing at Melrose, in the county of Montgomery and State of Pennsylvania, have invented certain new and useful Improvements in Packages for Cotton-Battling, of which the following is a specification.

My invention relates to the manner of packing cotton, wool, etc., in suitable packages for the retail trade, and is designed more particularly as a means for packing what is known to the trade as cotton batting which consists of a pressed sheet of carded cotton or cotton waste folded and afterwards rolled into a convenient bundle. A large number of packages thus formed are then baled or cased for shipment and it is during the packing and unpacking of the bales or cases that the packages are frequently broken and the contents disarranged in such a manner as to cause great inconvenience in handling and a consequent depreciation in the value of the stock. In order to obviate this difficulty I secure the wrapper in such a manner that the fastening or locking means will be located at or near the center of the package so that pressure from without in baling or casing the packages will not tend to release the wrapper from the fastening means nor the fastening means from the contents of the wrapper.

My invention will be more fully understood by reference to the accompanying drawings, in which:

Figure 1 illustrates a perspective view of a roll of cotton batting prior to receiving a wrapper. Fig. 2 illustrates a similar view with the cotton batting partly inclosed by the wrapper and the ends folded up ready to be secured by fastening pins. Fig. 3 represents a like view with the fastening pins in proper position. Fig. 4 shows the same with seals pasted or otherwise secured to the ends of the package to prevent any accidental withdrawal of the pins. Fig. 5 illustrates a package slightly modified in shape, being approximately square in cross section and being secured by staples interposed between the folded ends of the wrapper and the contents of the package, and Fig. 6 represents a horizontal section on line 6—6 of Fig. 4.

Referring to the reference letters of the drawings, A, represents a pressed sheet of

cotton batting which as shown in Figs. 1 and 6, is folded and afterwards rolled into the form of a cylindrical bundle.

B, represents the wrapping sheet which, as shown in Fig. 2 is of somewhat greater width than the roll of cotton batting and which is tucked or folded in at the ends as shown at b, b; the last fold as shown being secured to the subsequent folds and to the contents of the package by pins C, C. To prevent the removal of these pins by accident the ends of the package are provided with stamps or seals D, D which are pasted over the folded ends of the package and inclose the pins in order to hold the pins in position.

In Fig. 5 of the drawings I have shown a slightly modified form of my invention in which case the package is square instead of circular in cross section and in lieu of the pins C, C, I provide staples C', C' for the purpose of securing the ends of the wrapper to the contents of the package.

Having described my invention what I claim and desire to secure by Letters Patent is:

1. A package comprising a layer of cotton batting, compactly folded and afterwards rolled into a compact mass, a wrapping sheet surrounding the same and being of sufficient width to allow the ends thereof to be turned in to form overlapping folds against the ends of the package, fastening pins adapted to pass through the overlapping folds and to be embedded in and held by the contents of the package and seals inclosing the fastening pins for the purpose specified.

2. A package, comprising a sheet of carded cotton batting having the sides compactly folded toward the center and afterwards tightly rolled into a compact mass, a wrapping sheet of greater width than the batting tucked in at the ends to form overlapping folds, pins engaging these folds and extending some distance into the mass of batting and held in place by engagement with the contents of the package and seals laid over the pins and secured by pasting to the ends of the wrapper substantially as described.

In testimony whereof I affix my signature in presence of two witnesses.

DEL ROY F. FOWLER.
